UNITED STATES PATENT OFFICE.

HARRY J. CRINER, OF DAVENPORT, IOWA, ASSIGNOR OF ONE-HALF TO A. G. BUSH, OF DAVENPORT, IOWA.

CONTROL MECHANISM FOR WRINGERS.

Application filed September 15, 1927. Serial No. 219,705.

My invention relates to improvements in devices for adjusting the position of a clothes wringer mounted upon a washing machine or other appliance and for locking the wringer 5 in its adjusted position; also for automatically locking the driving mechanism out of gear while the wringer is being moved from one position to another.

The objects of my invention are:

- 10 1. To provide a simple, efficient, economical and easily operated and assembled mechanism to lock a wringer in a fixed position upon its supporting column;
- 15 2. To provide simplified means for automatically locking a swinging wringer out of gear while swinging it from one position to another;
- 20 3. To provide means for locking a swinging wringer in a fixed position whenever it is in gear;
- 25 4. To provide means for locking a swinging wringer in fixed position which cannot be operated to unlock the wringer so long as the driving mechanism is in gear.

I attain these objects by the means illustrated in the accompanying drawings, in which,—

Figure 1 is a sectional elevation of my gear housing and control apparatus on the line 30 1—1 of Figure 3; Fig. 2 is a horizontal sectional detail of my housing showing a part of the clutch therein, with the horizontal gear sleeve broken away, the housing being in section on the line 2—2 of Fig. 1; Fig. 3 is a vertical sectional view of my housing on the line 35 3—3 of Fig. 1, but shows the locking bar and part of the control lever, the gear shifting arm and the drive shaft, 4, in solid lines; Fig. 4 is a detail showing a top view of the shift 40 lever; Fig. 5 is a sectional detail showing the application of the housing to the supporting column.

Similar numbers refer to similar parts throughout the several views.

My appliance comprises a housing, 2, substantially in the well-known form which is in common use and which has a projecting cylindrical portion, 2'', at the lower end thereof, with a flange portion, 2', formed integral therewith. My device may be mounted upon the ordinary supporting column, 1, which carries a vertical drive shaft, the extended cylindrical portion, 2'', of the housing seating within the upper end of the sup-

porting column, 1, and the flange, 2', resting 55 upon a corresponding flange formed upon the upper end of the supporting column, 1.

A plurality of openings, 17'', are formed in the flange at the top of the supporting column, 1, with corresponding openings, 17', 60 formed in the flange, 2', of the housing.

A locking bar, 17, is slidably mounted in the housing, 2, with a coiled tension spring, 19, mounted upon the lower end thereof bearing against a suitable pin or detent, 19', and 65 acting to force the locking bar, 17, downward into the openings, 17' and 17''.

A control lever, 11, has one end secured to the upper end of the locking bar, 17, by a pin, 18, or other suitable means. A shift arm, 15, is united to the lever, 11, and extends downwardly through an opening, 15', in the top of the housing into the housing, and its lower end extends between a pair of flanges, 9 and 9', formed upon the sleeve, 10, to which 75 the bevel gears, 7 and 8, are splined or otherwise suitably secured.

The control handle normally rests in the position shown in Figure 3 and is detained in its normal position by the head of a pin, 13, secured to the control lever near the middle thereof, the head of said pin, 13, resting in the hollows, 14^a, formed in the top of the lugs or shoulders, 14 and 14', which are formed integral with the upper portion, 3, 85 of the housing 2. The housing, 2, is preferably formed with its upper portion, 3, secured thereto by stud bolts, 3', for convenience of assembly, but may be formed in one piece or the form thereof may be varied as desired 90 to suit the requirements of each particular case.

The shaft, 6, of the drive roll of the wringer is mounted in the center of the housing, 2, and the sleeve, 10, is slidably mounted 95 thereon so that when the handle, 12, of the control lever, 11, is moved to the right as shown in Figure 1, the bevel gear, 7, will mesh with the bevel gear, 5, mounted upon the upper end of the drive shaft, 4, and when 100 the handle, 12, is moved to the left, the bevel gear, 8, will mesh with said bevel gear, 5. When the handle, 12, is in its middle position, it may be moved downwardly between the lugs, 14 and 14', and when so moved, the 105 downwardly projecting portion of the lever, 11, will fulcrum upon the edge of the housing adjacent the rear of the opening, 15'. When

the handle, 12, is moved downwardly using the portion designated as a fulcrum, it will lift the rear end of the control lever, 11, thus raising the locking bar, 17, so that the lower end thereof will clear the openings, 17", in the flange of the supporting column, 1, and permit the wringer to be swung around upon the supporting column. A plurality of openings, 17", are formed in the supporting column flange and their number and position may be varied as desired.

It should be noted that the lower end of the shift arm, 15, in its normal position while secured between the flanges, 9 and 9', does not extend downwardly clear to the sleeve, 10, there being sufficient clearance to permit the shift arm, 15, to move downward as far as necessary in raising the locking bar, 17, sufficiently to clear the openings, 17", in the flange and supporting column.

It is obvious that the form and proportions of my device may be varied to a considerable extent without departing from the spirit of my invention.

25 1. I claim:

1. In a wringer control mechanism, the combination with a supporting column, of a housing revolvably mountable thereon, a locking bar slidably mounted within the housing, 30 a control lever having one end united to the upper end of the locking bar and fulcrumed upon the housing, a slot formed in the top of the housing, a shift arm united to the control lever and extending downwardly through the 35 slot into the housing, and means within the housing controllable by the shift arm for throwing the wringer into and out of gear.

2. In a wringer control mechanism, the combination with a flanged supporting column 40 having openings formed in the flange, of a housing revolvably mountable thereon, a locking bar slidably mounted within the housing adapted to enter the flange openings and be thus engaged by the flange, a control 45 lever having one end united to the upper end of the locking bar and fulcrumed upon the housing, a slot formed in the top of the housing, a shift arm united to the control lever and extending downwardly through the slot 50 into the housing, and means within the housing controllable by the shift arm for throwing the wringer into and out of gear.

3. In a wringer control mechanism, the combination with a flanged supporting column 55 having openings formed in the flange, of a housing revolvably mountable thereon, a locking bar slidably and pivotally mounted within the housing adapted to enter the flange openings and be thus engaged by the flange, a control lever having one end united to the upper end of the locking bar and fulcrumed upon the housing, a slot formed in the top of the housing, a shift arm united to the control lever and extending downwardly 60 through the slot into the housing, and means

within the housing controllable by the shift arm for throwing the wringer into and out of gear.

4. In a wringer control mechanism, the combination with a flanged supporting column having openings formed in the flange, of a housing revolvably mountable thereon, a locking bar slidably mounted within the housing adapted to enter the flange openings and be thus engaged by the flange, a control lever having one end united to the upper end of the locking bar and fulcrumed upon the housing, a slot formed in the top of the housing, a shift arm united to the control lever and extending downwardly through the slot into the housing, means within the housing controllable by the shift arm for throwing the wringer into and out of gear, and means 70 united to the housing to lock the shift lever against lateral movement when the locking 75 bar is disengaged from the flange.

5. In a wringer control mechanism, the combination with a flanged supporting column having openings formed in the flange, of a housing revolvably mountable thereon, a locking bar slidably mounted within the housing adapted to enter the flange openings and be thus engaged by the flange, a control lever having one end united to the upper end of the locking bar and fulcrumed upon the housing, a slot formed in the top of the housing, a shift arm united to the control lever and extending downwardly through the slot into the housing, means within the housing controllable by the shift arm for throwing the wringer into and out of gear, and means 80 united to the housing to lock the shift lever against lateral movement when the locking 85 bar is disengaged from the flange.

6. A control mechanism comprising a flanged supporting column having a drive shaft mounted therein and carrying a drive gear, a gear housing and wringer support revolvably mounted thereon, openings in the flange, a locking bar slidably mounted and rotatable in the housing having its lower end adapted to enter any of the flange openings when registering therewith, a control lever pivoted to the upper end of the locking bar and fulcrumed upon the housing, a drive-roll 105 shaft mounted in the housing, a doubly flanged sleeve slidably mounted upon the roll shaft within the housing and carrying driven gears at the opposite ends thereof, a longitudinal slot in the upper part of the housing, a shift arm united to the control lever extending through the slot into the housing and between the sleeve flanges, detents united to the housing on both sides of the shift lever, and locking same against a lateral movement when in neutral position.

7. A control mechanism comprising a flanged supporting column having a drive shaft mounted therein and carrying a drive gear, a gear housing and wringer support 110

- revolubly mounted thereon, openings in the flange, a locking bar slidingly mounted and rotatable in the housing having its lower end adapted to enter any of the flange openings 5 when registering therewith, a control lever pivoted to the upper end of the locking bar and fulcrumed upon the housing, a drive-roll shaft mounted in the housing, a doubly flanged sleeve slidingly mounted upon the 10 roll shaft within the housing and carrying driven gears at the opposite ends thereof, a longitudinal slot in the upper part of the housing, a shift arm united to the control lever extending through the slot into the 15 housing and between the sleeve flanges, detents united to the housing on both sides of the shift lever, and locking same against a lateral movement when in neutral position, and adapted to lock the shift lever against 20 downward movement when in gear either forward or reverse.
8. A control mechanism comprising a flanged supporting column having a drive shaft mounted therein and carrying a drive 25 gear, a gear housing and wringer support revolubly mounted thereon, openings in the flange, a locking bar slidingly mounted and rotatable in the housing having its lower end adapted to enter any of the flange open- 30 ings when registering therewith, a control lever pivoted to the upper end of the locking bar and fulcrumed upon the top of the housing, a drive-roll shaft mounted in the housing, a doubly flanged sleeve slidingly mount- ed upon the roll shaft within the housing 35 and carrying driven gears at the opposite ends thereof, a longitudinal slot in the upper part of the housing, a shift arm united to the control lever extending through the slot into the housing and between the sleeve flanges, detents united to the housing on both sides of the shift lever, and locking same against a lateral movement when in neutral position. 40
9. A control mechanism comprising a flanged supporting column having a drive shaft mounted therein and carrying a drive gear, a gear housing and wringer support revolubly mounted thereon, openings in the flange, a locking bar slidingly mounted and 45 rotatable in the housing having its lower end adapted to enter any of the flange openings when registering therewith, a control lever pivoted to the upper end of the locking bar and fulcrumed upon the housing, a drive-roll shaft mounted in the housing, a doubly flanged sleeve slidingly mounted upon the roll shaft within the housing and carrying driven gears at the opposite ends thereof, a longitudinal slot in the upper part of the housing, a shift arm united to the control lever extending through the slot into the housing and between the sleeve flanges, and 50 detents united to the housing on both sides of the shift lever. 55

In testimony whereof he affixes his signature.

HARRY J. CRINER.
